UNITED STATES PATENT OFFICE.

ADOLPH L. DE LEEUW, OF CINCINNATI, OHIO, ASSIGNEE TO THE CINCINNATI MILLING MACHINE COMPANY, A CORPORATION OF OHIO.

OILING SYSTEM.

1,093,118.

Specification of Letters Patent. Patented Apr. 14, 1914.

Application filed June 23, 1913. Serial No. 775,200.

To all whom it may concern:

Be it known that I, ADOLPH L. DE LEEUW, a citizen of the United States, and residing at Cincinnati, in the county of Hamilton and State of Ohio, have invented a new and Improved Oiling System, of which the following specification is a full disclosure.

This invention relates to a machine tool oiling system and it proposes a frame organization such that oil will be automatically elevated from a lowermost well or point to an uppermost reservoir, from which it will be gravimetrically distributed to the various wearing surfaces, largely by means of conduits integral with the main casting or frame of the machine.

A primary object of this invention is to create a gravimetric oil distributing frame in which oil will be kept in continuous circulation throughout all of the wearing surfaces, and will be ultimately drained to an oil well, and then elevated to an uppermost distributing point, and then led by appropriate channels arranged in what may be termed parallel series as distinguished from multiple series, so that each bearing releases its contaminated oil directly to the well, and not to other bearings.

Heretofore an oiling system has been proposed in which oil was drawn from a well in the frame of the machine and then distributed to an uppermost wearing surface, from which it was released in a more or less contaminated condition and caused to pass through another bearing, which further contaminated it, and in turn released it into another bearing, and so on, until ultimately it was permitted to return to the oil well after having been successively contaminated by passing through several bearings. When it reached the oil well it was of course diluted by a larger mass of oil so that it was suitable for reapplication to the bearings. This system, while not injurious on the first reached bearing, was objectionable as to subsequent bearings, for the reason that the latter received oil containing an undue percentage of impurity. A drop of highly contaminated oil added to the well would be so diluted as to be harmless so that a drop taken from the well would represent good lubricating material, but as soon as this drop passed through the first bearing it would be contaminated by a certain percentage of impure matter, the percentage of

course being very much higher than before it passed through the bearing, *i. e.*, much higher than the average value of the bulk of oil in the well. To add this contaminated drop to the next bearing is bad practice, because of its increased contamination, and after it had passed through the second bearing it would be still further contaminated and even less fit for the third bearing, and so on.

The construction proposed by this invention overcomes the above-mentioned objections, for the same quality of oil is fed to each bearing, this quality being the average value of the bulk of oil in the well, and when the oil has been enriched with contamination by passing through the bearing it is discharged directly into the well, and thus its impurities are greatly diluted before it reaches the next bearing by recirculation through the system.

Another object is to render available a simple frame design that will automatically effect the oiling of the various bearings in the way aforesaid, without requiring an extensive built-up structure, and by enabling the major features to be produced by a simple casting process in the foundry.

Another object is to devise a milling machine frame that will especially provide for this system of oil distribution.

Other objects will be in part obvious from the annexed drawings and in part indicated in connection therewith by the following analysis of this invention.

This invention accordingly consists in the features of construction, combination of parts, and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a side elevation partly in section of a milling machine frame embodying the oil distributing characteristics proposed by this invention. Fig. 2 is a detailed sec-

tion taken through line 2—2 of Fig. 1, showing further details of the same. Fig. 3 is a side elevation, partly in section, of a milling machine having a vertical spindle also embodying the features of this invention. Fig. 4 is a section through line 4—4 of Fig. 3, showing the internal construction of the frame.

Continuing now by way of a more detailed description, the construction of the horizontal spindle miller will first be described.

The frame consists of a base 1, from which rises a column 2, which preferably is a one-piece casting having guides 3 for the usual mounting of the knee, etc. At its top this frame may be constructed to receive the overarm either in the conventional way or preferably after the construction of my pending application Serial No. 766,905, filed May 10, 1913, which form is here illustrated by Figs. 1 and 2, and comprises a truss-like overarm 4 having a dove-tailed slide 5 interfitting with a dove-tailed slide-way 6 machined into the top of the column. At an appropriate point in the top of the column a pocket 7 is formed by means of the side walls of the frame, and a transverse web 8 which is contoured to form the features to be hereinafter described. An oil-pipe 9 enters the pocket 7 at any suitable point, as for example from the exterior of the frame, and enables oil to be forced up into said pocket in abundant quantities by an oil pump 10 mounted on the base of the machine and driven by a belt 11 and pulleys 12 and 13 from the main driving shaft 14 of the machine.

Leading in opposite directions from the pocket 7 are two spill-ways 15 and 16 which are preferably crowned slightly, as shown by Fig. 2, to form gutters 17. At a point slightly above the gutter 17 in one of its spill-ways, as for example, in the spill-way 16 is a discharge aperture 18 from which leads an overflow pipe 19 directed toward the bottom of the column, and through which excess oil delivered by the pump will flow. The spill-way 15 and the gutter 17 thereof lead to a pocket 20 above the front bearing of the spindle, and an oil duct 21 permits the oil to drain to the wearing surfaces, and from the latter it flows ultimately to the oil well in the base. In like manner the spill way 16 drains into a pocket 22, which, by means of a duct 23 similarly supplies the rear bearing of the spindle.

At a suitable point in the side of the frame is an opening 24, and bolted into this opening is a drive-unit 25 which is separately manufactured as a distinct structural entity and contains sundry gear-wheels and shafts constituting a power transmitting organization and which is subsequently bolted in place on the main frame or column 2. This

transmission unit provides extensions 26 and 27 that enter the interior of the column and the upper surfaces of which are provided with canals 28 and 29 having suitable ripples for diverting oil and having suitable oil ducts 30 and 31 for feeding oil from the same to the bearings. These canals are supplied with oil by means of pipes 32 and 33 that lead from pockets 22 and 20 and which are bent into position to bring their lower ends above the upper portion of the canals 26 and 27. Another gear insert unit is indicated by 34, and in this instance, it constitutes a speed change organization, and it is supplied with oil preferably from the overflow pipe 19. The construction of these insert units will be further detailed in connection with the vertical spindle machine. After the oil has left the various wearing surfaces aforesaid, it flows to the base of the machine and through a vent 36 to an oil well 37 from which it is raised by the pump 10 as aforesaid.

The vertical spindle organization is shown more clearly by Figs. 3 and 4, and will now be described. The column 40 of this machine rises from a suitable base 41 and terminates in a head 42 in which is journaled the vertical spindle 43 by means of bearings 44 and 45. At its upper end, an annular reservoir 46 is provided, which discharges the oil by means of an overflow 47 onto a web 48 preferably cast integral with the frame. The oil is conveyed to the bearing 44 by means of the groove 49 leading from the annular reservoir 46, and it passes down the spindle to the lower bearing 45 from which it is thrown off onto the main frame by the oil-ring 50, and it then flows down the incline 51 and ultimately to the oil well in the base. It is to be noted here that although in this instance the oil flows from the bearing 44 to the bearing 45, no undue contamination is experienced, since the bearing 44 carries hardly any load at all, it being relieved from thrust by the bearing 45. The web 48 is cast into a trough-like form having an upturned edge or lip 52 which inclines from the head 42 toward the rear end of the column, and suitably spaced are dams 53 and 54 that divert the oil sufficiently to cause it to flow down small drain pipes 55, 56 and 57. The drain 55 leads to the forward bearing 58 of a driving shaft 59, and the pipe 56 leads to the rear bearing of said shaft, and after the oil has passed through these bearings it dribbles down the frame of the machine toward the base and into the oil well. This column, like that of the horizontal spindle, also has a similar opening 24 that receives a similar transmission unit 25 containing frame extensions 26 and 27 providing canals 28 and 29 from which lead ducts 31 and 32 to the various bearings of the transmission unit. Thus,

the canal 28 provides a pool 60, into which oil is directly delivered by the pipe 57 and it then overflows the edge of the pool 60 and passes down the canal, being diverted at intervals by means of dams 61 and 62 to insure its flow through the ducts 31 to the various bearings, as shown by Fig. 4. The oil overflowing the canals 28 and 29 and discharging from the various bearings then 10 passes directly to the oil well in the base.

Leading from a lower point of the web 48 is an overflow pipe 63 that discharges into the pool 64 of the speed change insert unit 34, and the oil then flows over the spill-way 65 and the successive dams 66 and 67, and finally through the discharge gutter 68 down to the well. Ducts or oil holes 69 lead to the various bearings of this unit, and the latter in turn discharge the contaminated oil to the central well, where it is diluted and returned to the system.

It will thus be perceived that this invention is well adapted to achieve the objects aforesaid in a simple and direct manner, 25 and in a way preventing the admission of unduly contaminated oil onto any of the bearings.

Without further elaboration, the foregoing will so fully reveal the gist of this invention that others can by applying current knowledge readily adapt it for various applications without omitting certain features that, from the standpoint of the prior art, fairly constitute essential characteristics of 35 the generic or specific aspects of this invention, and therefore such adaptations should and are intended to be comprehended within the meaning and range of equivalency of the following claims.

40 Having thus revealed my invention, I claim as new and desire to secure by Letters Patent of the United States:—

1. A machine-tool oil-distributing organization of the nature disclosed combining a 45 hollow frame providing an overhanging head having a vertical bearing, a vertical spindle journaled in said bearing, said frame providing an uppermost pocket having an oil-drainage into said bearing and having an overflow into a lower oil distributing canal provided by said frame, a horizontal shaft 50 interiorly journaled to said frame and having a driving relation with said spindle, the bearings of said shaft being arranged to receive oil drainage from said canal, an oil-well at the base of said frame for receiving oil-returns, and a pump for elevating oil from said well to said uppermost pocket.

2. A machine-tool oil-distributing organization of the nature disclosed combining a 60 hollow frame providing an overhanging head having a vertical bearing, a vertical spindle journaled in said bearing, said frame providing an uppermost pocket having an oil-drainage into said bearing and having

an overflow into a lower oil distributing canal provided by said frame, a plurality of bearings located below said canal, a plurality of individual conduits each receiving oil directly from said canal and conveying it directly to one of said bearings, an oil-well at the base of said frame for receiving oil-returns, and a pump for continuously elevating oil from said well to said uppermost pocket. 70

3. A machine-tool oil-distributing organization of the nature disclosed combining a hollow frame providing an overhanging head having a vertical bearing, a vertical spindle journaled in said bearing, said frame providing an uppermost pocket having an oil-drainage into said bearing and having an overflow into a lower oil-distributing shelf-like canal interiorly provided by one side of said frame, a journal-box interiorly provided by said frame below said canal and having a conduit for receiving oil drainage therefrom, an oil-well at the base of said frame for receiving oil-returns from said bearings, and a pump for elevating oil from 80 said well to said uppermost pocket. 85

4. A machine-tool oil-distributing organization of the nature disclosed combining a hollow frame providing an overhanging head, having a vertical bearing, a vertical 95 spindle journaled in said bearing, said frame providing an uppermost pocket having an oil-drainage into said bearing and having an overflow into a lower oil distributing canal interiorly integral with said frame, a horizontal shaft interiorly journaled to said frame and having a driving relation with said spindle, each bearing of said shaft being arranged to receive oil directly from said canal, a plurality of other bearings below 100 said canal, a conduit for each of said other bearings receiving oil directly from said canal, an oil-well at the base of said frame for receiving oil-returns, and a pump for continuously elevating oil from said well to 105 said uppermost pocket. 110

5. A machine-tool oil-distributing organization of the nature disclosed combining a frame having a vent in its upper part and an oil well in its lower part, a pump for 115 continuously elevating excess oil from said well to said vent, a trunk-line over-flow oil-course interiorly provided by said frame for conducting excess oil from said vent to said well, a plurality of branch-line conduits each individually leading from said trunk-line oil-course to said well, and a single bearing in each of said branch-line conduits. 120

6. A machine-tool oil-distributing organization of the nature disclosed combining a hollow main-frame providing bearings for a driven shaft and having a large opening in its side, a supplemental-frame providing 125 bearings for a driving shaft and secured to 130

4
said main frame at its large opening, said main-frame providing an elevated oil vent having an oil-drainage to the main frame bearings and having a conduit leading to the supplemental-frame bearings, an oil well at the base of said main-frame for receiving oil-returns from all of said bearings, and a pump for elevating oil from said well to said vent.

10 7. A machine-tool oil-distributing organization of the nature disclosed combining a hollow main-frame providing bearings for a driven shaft and having a large opening in its side, a supplemental-frame providing 40 bearings for a driving shaft and secured to said main-frame at its large opening, said main-frame providing an elevated oil pocket having an oil-drainage to the main-frame bearings and having a conduit leading to 45 an oil pocket provided by said supplemental-frame, the latter having an oil drainage to the supplemental-frame bearings, an oil well at the base of said main frame for receiving oil returns from all of 50 said bearings, and a pump for elevating oil from said well to said pocket.

8. A machine-tool oil-distributing organization of the nature disclosed combining a hollow main-frame providing bearings for a driven shaft and having a large opening in its side, a supplemental-frame providing 55 bearings for a driving shaft and secured to said main-frame at its large opening, said main frame providing an elevated oil pocket overflowing into a canal having an individual oil-drainage to each of the lower

5 main-frame bearings and having a conduit leading to an oil pocket provided by said supplemental-frame, the latter having an individual oil drainage to each of the supplemental-frame bearings, an oil well at the base of said main-frame for receiving oil returns from all of said bearings, and a pump for elevating oil from said well to 45 said pocket.

9. A machine-tool oil-distributing organization of the nature disclosed combining a hollow main-frame providing bearings for a driven shaft and having a large opening in its side, a supplemental-frame providing 50 bearings for a driving shaft and secured to said main frame at and having a portion projecting into its large opening, said main-frame providing an elevated oil pocket having an oil-drainage to the main-frame bearings and having a conduit leading to an oil 55 pocket provided by said supplemental-frame, said pocket having an oil drainage to the supplemental-frame bearings and also having an overflow into the interior of said main-frame, an oil-well at the base of said main-frame for receiving oil returns from all of said bearings, and a pump for elevating oil from said well to said pocket.

In witness whereof, I hereunto subscribe my name, as attested by the two subscribing witnesses.

ADOLPH L. DE LEEUW.
